ARC LAMP AND CIRCUIT THEREFOR

David Reichinstein, Zurich, Switzerland

Application February 26, 1946, Serial No. 650,354
In Switzerland March 7, 1945

5 Claims. (Cl. 315—102)

1

It is usual in enclosed gas-discharge lamps, whose light derives exclusively from the incandescent electrodes, to use spherical or hemispherical tungsten electrodes. Electrodes of this type present the drawback that their reverse sides are less incandescent than those that face each other, and for this reason do not emit sufficient light.

Extensive experiments carried out by me have led to the result that it is advantageous to employ hollow hemispherical electrodes, and in general electrodes with concave-convex faces. The hollowing of the electrodes renders them thinner, and consequently the outer faces become just as incandescent as the inner ones.

Further experiments led to the result that with the help of electrodes with concave-convex faces the irradiation in a desired direction can be greatly amplified, other things being equal, if the electrodes are so fitted that their inner sides do not exactly face each other—in which case the rays from the inner side of one electrode are caught by the inner side of the other, and vice versa—but by fitting the electrodes so that they are somewhat rotated round their axis. In this case the inner sides of both electrodes direct their rays at least partially outwards in a desired direction.

The accompanying drawing illustrates by way of example a satisfactory embodiment of the invention. In said drawing:

Fig. 1 shows a top view of the main electrodes of the lamp;

Fig. 2 shows schematically a lamp constructed in accordance with the invention;

Fig. 3 represents a circuit for operating the lamp; and

Figs. 4 and 5 show diagrammatically the various steps in the operation of the switches shown in Fig. 3.

Fig. 1 shows the arcuate electrodes 6 and 7 in rotated position. It is evident that, as a result of the rotation of the electrodes, distance 13 is smaller than distance 12. The arrow in the center of the figure indicates the direction of the desired irradiation. Nevertheless, in this case too, the most valuable portion of the light emitted by the two facing sides of the electrodes is lost.

As regards the electrodes, the present invention consists in providing the parts of the two electrodes that face each other with holes. These holes are not, however, at the same level; i. e. do not lie opposite each other. For instance, incandescent electrode 6 can emit rays through holes 10 and 11 in electrode 7, and the corresponding

2

incandescent part of electrode 7 can emit rays through holes 8 and 9 in electrode 6.

By surrounding the electrodes with a projecting mirror in such a way that not only the irradiation of the inner sides of the electrodes through the holes, but also that of their outer sides, is directed in the line of projection, the irradiation can be utilized to a high degree for purposes of projection.

10 Lamps fitted with a projecting mirror of this type can be employed not only for projection purposes, but also for illuminating large rooms and even streets.

The lamp 14 is reproduced in its entirety in Fig. 2. Here 15 is the glass bulb, whose neck 16 can in very powerful lamps be surrounded with a cooling water jacket. In neck 16 is suspended cylinder 17, called the chimney. The space between neck 16 and chimney 17 is filled with steel wool 18 for the purpose of intercepting the sublimed particles of tungsten, in order to prevent the sides of the bulb from becoming covered with soot through long usage.

Close to main electrodes 19 and 20 is fitted auxiliary electrode 21. Their conductors are welded into crystal base 22 and terminate in 4 firmly fixed pins 23 for plugging into a four-pole socket. The lamp can be filled with a pure inert gas or with a mixture of inert gases, one of which is nitrogen.

30 With respect to the circuit, the present invention is characterized in that the arc lamp is fed from a lighting main or electrical distribution network of any voltage over a simple 4 or 3 step switch and with the insertion of a small transformer. The last step of the switch connects the lamp directly to the main and at the same time excludes the transformer.

In Fig. 3, 51 represents the lighting main. 36, 46 and 38, 39 are two primary windings of the transformer. If the voltage of the main is 220 volts these two windings are connected in series, if it is 120 volts they are connected in parallel. In both cases secondary winding 40, 42 gives an E. M. F. of 420 volts, while the other secondary winding 43, 41 connected in series with the former gives 20 volts. This second winding is also utilized for heating the wire of the auxiliary electrode of the lamp. 44, 49, 45 are impedances; 6 and 7 are the main electrodes of the lamp, while 21 represents the wire of the auxiliary electrode; 29, 30, 33, 34, 24, 26, 28, 27, 25 represent a 4-step switch that can effect the following connections by the actuation of a single lever:

Step 1.—Connects 29 with 33 and 30 with 34, whereby main 51 is connected over terminals

31, 32 to the primary winding of the transformer.

Step II.—Connections 29, 33 and 30, 34 are maintained, but at the same time 24 is connected with 26 and 28 with 27. Thereby main electrode 6 is connected with terminal 40 of the secondary winding over impedances 49 and 44, while terminal 41 of the secondary winding is connected with auxiliary electrode 21 over 28, 27. By pressing the button of switch 35 the wire of auxiliary electrode 21 is connected with the 20-volt secondary winding of the transformer and becomes incandescent. This results in the formation of an auxiliary arc between 21 and main electrode 6.

As soon as the main electrode is heated to a dull red the switch can be turned to step III.

Step III.—Connections 29, 33 and 30, 34 are maintained as is connection 24, 25, while 28 is now connected to 26. Thereby the other main electrode is connected with terminal 41 of the secondary winding of the transformer, while incandescent lamp 50 is inserted in the circuit of the auxiliary arc. The ohmic resistance of lamp 50 must be much greater than the sum of 44 and 49 and is so determined that the arc passes on to the second main electrode. When the latter is sufficiently heated by the arc, lamp 50 is extinguished. A vital part of the present invention consists in that the automatic extinction of lamp 50 affords an indication that the arc lamp can be switched directly over to the main step IV.

Step IV.—Connections 29, 33 and 30, 34 are broken, while 24 is connected with 29 and 25 with 30. This completely excludes the transformer and connects the lamp to the main.

It should be mentioned that step I can be eliminated, while on the other hand the lever switch can be replaced by a roller switch. Nevertheless the following description of the lever switch will go to prove that such a device possesses particular simplicity and handiness.

Small copper plates are fitted at different levels on the inside of two semi-circular sheaves made of insulating material and facing each other. A lever, also of insulating material, rotates round an axle placed beneath the plates. This lever is fitted with metal pins which, on turning the lever, engage in hollows in the plates here symbolized by small circles. In Fig. 4 can be seen triple plate 52 which is connected with single plate 54 situated on the third level of the insulating sheave by copper wire 53 fitted on the outside of the sheave. Single plate 62 must be fitted on the second level in step IV of the opposite semi-circular sheave Fig. 5, in the upper level of which is fitted triple plate 59. It is evident that, in order to achieve a practical and simple connection of single plate 62 with triple plate 63 on the first level, the latter must likewise be fitted on the same sheave Fig. 5 on which is fitted plate 59. The latter, and triple plate 58 on Fig. 4 as well, are not permanently connected to the main, but with the primary winding of the transformer, and are identical with contacts 33 and 34 in Fig. 3.

It should also be mentioned that double plate 55 on the third level of Fig. 4 is symbolized in Fig. 3 by contact 26, while 52 and 54 are identical with 29. Plate 56 of Fig. 4 is identical with 27 in Fig. 3; triple plate 60 on the third level of Fig. 5 corresponds to contacts 24 in Fig. 3; double plate 61 on the second level of Fig. 5 corresponds to contacts 28 in Fig. 3, and 62 and 63 correspond to contacts 30 in Fig. 3.

As, however, single plate 62 is fitted on the second level, triple plate 63 must be fitted on the first level, in order that it may be easily con-

nected with the former by wire 64. It will be seen that in step IV only plates 54 and 57 on the sheave represented in Fig. 4 are connected with plates 60 and 62 on that represented in Fig. 5, while transformer connections 58, 59 are broken.

Summing up, this switch can be designated as a 4 or 3 step, 2-pole sliding lever switch.

With respect to the circuit, it is characterized first of all by the automatic extinction of lamp 50 10 as a signal for switching over to the main. Secondly this circuit is characterized by the compensating introduction in the 440-volt circuit of the secondary winding of the transformer of a current of such intensity as to give rise to a suitable voltage at the terminals of the arc lamp for the purpose of switching over to an appropriate lighting main by inserting adequate impedance 49. For this reason the circuit can be designated as a signal-compensation circuit.

20 I claim:

1. An arc lamp supplying a continuous spectrum and comprising a glass bulb provided with a neck and containing an inert gas, a wire auxiliary electrode, a manual switch connected with 25 the latter, perforated main electrodes arranged at the same elevation and presenting convex surfaces to each other, the rear surfaces of the main electrodes being concave, said main electrodes being mounted in rotated relation with respect to 30 each other and are so mutually disposed that, viewed in section along the central plane common to said two main electrodes, the one pair of ends of the electrodes opposite one another have a greater distance from each other than the other 35 ends, for the purpose of obtaining a larger uncovered radiating electrode surface, a compensated network for connecting the lamp to an electrical distribution network and including a main current circuit and an auxiliary arc circuit, a 40 signal lamp in the auxiliary arc circuit, an impedance common to the main current and auxiliary arc circuits, the distance of the wire of the auxiliary electrode from the main electrodes and said common impedance on the one hand, and 45 such impedance and the impedance of the signal lamp on the other hand being so determined with respect to each other that upon simultaneous cutting in of the signal lamp and of the main current circuit, the signal lamp lights up and in a 50 short time is automatically extinguished, whereby there is provided a signal for switching the now glowing main electrodes to the distribution network.

2. Arc lamp according to claim 1 wherein the 55 main electrodes have concave-convex surfaces and are turned about their axes.

3. Arc lamp according to claim 1 including a glass cylinder inside of the neck of the bulb, the space between the inner wall of the bulb neck and 60 the outer wall of the glass cylinder being filled with steel wool for receiving the tungsten soot.

4. Arc lamp according to claim 1 wherein the auxiliary electrode is operated by a small voltage portion which is in series with the main voltage 65 operating the main electrodes, said auxiliary electrode being brought to incandescence by operation of the manual switch, the auxiliary arc thereby produced becoming automatically extinguished at a definite moment of the actuation of the 70 switch arrangement.

5. An arc lamp supplying a continuous spectrum and comprising a glass bulb provided with a neck and containing an inert gas, perforated, main electrodes arranged at the same elevation 75 and presenting convex surfaces to each other,

the rear surfaces of said main electrodes being concave, said main electrodes being mounted in rotated relation with respect to each other and being so mutually disposed that, viewed in section along the central plane common to the said electrodes, the one pair of ends of the electrodes opposite one another have a greater distance from each other than the other ends, for the purpose of obtaining a larger uncovered radiating electrode surface, a network connected with the lamp and including a multi-step switch, a transformer having a secondary coil comprising two parts connected in series, an auxiliary electrode, a common impedance, a second impedance, and a manual switch, said parts being connected electrically with each other and with one of the main electrodes when the first-mentioned switch is in one of its positions, the next position of the switch closing two circuits simultaneously, one of the said circuits containing both main electrodes while the other contains the auxiliary electrode and also a

5 signal lamp, said lamp having an impedance which is so dimensioned with respect to the other impedances and also with the impedance of the path between the auxiliary electrode and the main electrode that an auxiliary arc exists until the main arc glows fully, whereupon the auxiliary arc is automatically extinguished, said first-mentioned switch in its next position making connection only between the main electrodes, an impedance and the electrical distribution network.
